F. E. Maynard, ATTORNEY.

UNITED STATES PATENT OFFICE

WILLIAM B. TUBBS, OF LOS ANGELES, CALIFORNIA

PERMANENT HAIR WAVE ROD

Application filed May 9, 1929. Serial No. 361,772.

This invention relates to hair curling apparatus and more especially to permanent wave making devices.

In the art of producing waves in hair dressing a switch or hank of the hair of the patron is twisted on a rod and this is enveloped in a baker which is electrically heated. When the apparatus is removed the released hair takes a wavy set.

10 The usual form of rod is a plain cylinder and when the hair is released from it the hank has a tendency to take a screw curl. It is an object of this invention to avoid this curling effect and to cause the hair to lie in 15 smooth waves.

Therefore, the invention consists of a rod or tube of generally cylindrical form whose surface is provided with shallow undulations of uniform pitch, which may be of helical 20 form or of successive peripheral valleys.

Other objects, advantages and features of construction and mode of operation will be made manifest in the ensuing description of the herewith illustrative apparatus; it being 25 understood that modifications, variations and adaptations may be resorted to within the spirit, scope and principle of the invention as it is hereinafter more directly claimed.

30 Figure 1 is a side elevation of the rod.

Figure 2 is an end view thereof.

Figure 3 shows the application of the rod to a hank of hair.

Figure 4 is a side view of a helical groove 35 rod.

The preferred form of the device consists of a metallic rod or tube 2 of about one-quarter of an inch diameter and somewhat reduced at the scalp end 3 which is provided 40 with a diametrical slit 4 to receive a binding and tieing cord C.

At a suitable distance back from the end 3 the rod is provided with peripheral grooves 5 of shallow depth and about one-quarter inch pitch, preferably. The grooves are divided by ridges or beads in the form of truncated cones base to base; thus the ridges are more or less of angular contour rather than rounded, as, also, are the roots 50 of the grooves.

In Fig. 4 the grooves 5 are of helical form. In practice a hank of hair H is gathered and tied by cord C to the small end of the rod 2 and is then laid in a helix along the rod, crossing from groove to groove as shown 55 in Fig. 3, and again fastened.

Should the helical-groove rod 2 be used the hair is wrapped with a twist opposite to the pitch of the helix 5.

What is claimed is:

60 A device for use in permanent hair waving apparatus including a rod of generally cylindrical form and having shallow surface grooves in succession from near its scalp end; the grooves being formed between portions of truncated cone-like forms set base-to-base.

WILLIAM B. TUBBS.
